METHOD OF MAKING FIN RADIATORS

Wilbur G. Laird, Pleasantville, N. Y.

Application December 8, 1932, Serial No. 646,259

9 Claims. (Cl. 29—157.3)

This invention relates to the art of heat exchange, and more particularly to improvements in fin-tube radiators and method of manufacture.

One of the primary objects of this invention is to provide a fin-tube radiator having an improved joint of great strength and heat conductivity between the tube and a peripherally mounted fin.

A further object of the invention is to provide an efficient, rapid and simple method of assembling fin-tube radiators.

A still further object of the invention is to provide a construction and method of assembly for fin-tube radiators which will materially improve their appearance and reduce their cost without sacrifice of heat transfer capacity.

A feature of the invention is the production of a radiator of the fin-tube type embodying radiating fins of very thin section and relatively large radiating surface mounted transversely in spaced parallel relation on the tube, with an edge of each fin imbedded deeply in the metal wall of the heating tube, and with a metal-to-metal joint area between tube and fin surface substantially equal to the full imbedded surface area of the fin.

With these and other objects and features in view, the invention consists of the improved heat exchanger and method of assembly hereinafter described and more particularly defined in the accompanying claims.

In the following detailed description of the invention, reference will be made to the accompanying drawing, in which:

Fig. 1 is a top plan view of the improved fin-tube radiator.

Fig. 2 is an end view of the radiator of Fig. 1.

Figs. 3 and 4 illustrate two forms of split fins adapted for use in the radiator assembly of Fig. 1.

Fig. 5 is an enlarged side elevation, partly in longitudinal section, of a portion of a tube showing fins loosely seated in peripheral grooves thereof preparatory to assembly.

Fig. 6 is a transverse vertical section of the heating tube taken along the line 6—6 of Fig. 5.

Fig. 7 is a view corresponding to that of Fig. 5 illustrating the way in which the fins are imbedded in the tube walls after assembly.

Fig. 8 is an enlarged side elevation, partly in longitudinal section, of a portion of a tube having a helical groove in its outer wall.

Figs. 9 and 10 are respectively broken side and end elevations of one form of partially split fin adapted for mounting on the tube of Fig. 8.

Figs. 11 and 12 are respectively broken side and end elevations of another form of split fin adapted for mounting on the tube of Fig. 8.

The heat exchanger of the present invention is generally assembled from a peripherally grooved tube and a plurality of sheet metal fins. In assembling the radiator the general procedure is to seat an edge of one or more fins in each peripheral groove and then to apply pressure to the tube walls in a direction substantially at right angles to the faces of the seated fins to thereby crush the walls of the groove inwardly into tight gripping contact with each unit area of imbedded fin surface.

The embodiment of the heat exchanger which is illustrated in the drawing, comprises a fin-tube radiator (Fig. 1) having a plurality of split apertured sheet metal fins 16 mounted transversely in spaced parallel relation on a heating tube 18, with the central aperture edges of the fins 16 encircling and imbedded in the wall of the tube. The tube 18 is shown as a straight tube section enlarged at both ends to form threaded male and female coupling nipples 20 and 22 adapted for connection in a steam or other fluid heating system. As shown in Figs. 3 and 4, the fins 16 may be split along planes 24—24 passing horizontally or vertically through the central aperture 26, thus forming matched fin sections 28 and 30 (Fig. 3), 32 and 34 (Fig. 4). These matched fin sections are clamped in the tube walls to form in the assembled radiator the full equivalent of a single centrally apertured rectangular fin; and to simplify the description of the invention, the matched fin sections of Figs. 3 and 4 and the partially split fins of Figs. 9—12 will be generally defined throughout the description by the term "apertured split fin". The fins are split in order to facilitate rapid mounting thereof on the tube 18.

Preparatory to assembly, the tube 18 is formed with peripheral grooves 36 (Fig. 5) in its wall. The grooves are made wide enough so that the inner edges 38 of the fins are readily seated therein as a preliminary step in assembling the radiator. In the tube design of Fig. 5, the outer wall 45 of the heating section of the tube has a plurality of uniformly spaced circumferential endless grooves, while the tube of Fig. 8 is formed with a single encircling helical groove having a pitch substantially the same as the spacing of adjacent 50 grooves of Fig. 5.

The main heating section of tube 18, on which the fins are mounted, may have any cross-sectional shape, with the central apertures 26 of the fins cut to conform closely in contour and dimen- 55

sions with the base of the groove 36 on which the inner edge of the fin is to seat. Several advantages result from employing a tube of "tear-drop" section (Fig. 6). The apertures 26 of the fins shown in Figs. 3 and 4, are cut to fit the grooves of the tear-drop sectioned tube shown in Fig. 5. The split fin of Fig. 3 has a folded or double lapped "grommet" section 40 adjacent its inner edge, for the twofold purpose of reinforcing the fin and increasing somewhat the area of the neck through which heat is conducted from the tube to the fin.

The manner in which the radiator is assembled permits the use of very thin sheet copper in making up the fins. The complete radiator is very compact and light in weight for a given heating surface. Hard rolled sheet copper of 1/100-inch thickness is a suitable material for the fins, while the heating tube may be made of steel or aluminum. The largest internal diameter of the tube may be less than 1", with a wall thickness of about $\frac{1}{8}$ inch. The peripheral grooves in the tube walls may have a rectangular section of about 5/100 inch in depth,—or the grooves may have sides tapering from a width of, say, 4/100 inch at the top of the groove to 3/100 inch at the base. The commercial form of the radiator as designed for use in steam heating systems can be assembled into units of any desired capacity and length by coupling together sections chosen from two standard lengths measuring respectively 12" and 18". The split fins employed in these standard sections (Fig. 1) measure about 4" in width and 3" in height. The spacing of the grooves and fins on this radiator is normally about $\frac{1}{8}$ to $\frac{1}{4}$ inch center to center. End plates 42 and, optionally, reinforcing plates 44, are mounted transversely on the heating tube, to add strength to the radiator. The end plates and reinforcing plates are constructed of heavier metal than that used in making up the fins, and these plates are slightly wider than the fins.

The first step in the preferred method of assembling the radiator of Fig. 1, as illustrated in Fig. 5, involves seating the aperture edges of each matched half section of a split fin in a corresponding groove on the heating tube. To facilitate the performance of this assembly step, the upper half sections 32 (Fig. 4) of all of the fins required for the unit may have their edges 38 loosely seated in the grooves of the heating tube, after which the unit is turned over so that the weight of the unit holds the seated sections in place, while the matched lower sections 34 in turn have their inner edges seated on the groove. This operation when completed brings the upper and lower section of each split fin in contact along the edges abutting the plane of the split 24—24. The loose seating of the inner edges of the split fins in the peripheral grooves of the tube can be readily accomplished, as will be understood, by automatic machinery.

In assembling radiators employing tubes with a continuous helical groove encircling their periphery, of the type illustrated in Fig. 8, partially split fins may be employed, such as those shown in Figs. 9-12.

Such fins may consist of apertured rectangular plates partially split along a radial line 46 extending outwardly from the inner edge 38 of the plate. After the plates are partially split as shown, the inner or aperture edge of the fin is distorted by spreading apart the corner of the split edge (Figs. 10, 12) to impart to the inner edge of the fin a contour and helical pitch match-

ing that of the groove in the tube wall. To loosely seat the partially split fins as thus shaped in parallel spaced transverse relation in the groove, the fins are successively threaded onto the tube from one or both ends.

To allow for this method of assembly, the coupling nipple on at least one end of the heating tube will normally be reduced in size to permit the apertured fins to slip over it for engagement with the "thread" or helical groove in the tube wall, and the wall of the tube will be reduced in diameter at the threading end to taper off the depth of the groove so that the fin may be started on the thread of the groove.

A partially split fin of the general type illustrated in Figs. 9-12 may be used in a radiator assembly of the type shown in Figs. 1 and 5. To accomplish this, the inner edge of the fin should be partially split along a plurality of spaced radial lines, and the edge then pressed outwardly to form a split frusto-conical flange as illustrated by plate 17 of Fig. 5. After placing such fins in spaced relation on the tube with their inner edges 38 engaging an upper edge of the groove, pressure is applied laterally thereto to straighten the fin and loosely seat the inner edge thereof in the base of the groove.

After all of the split fins have been mounted in spaced relation on the heating tube with their inner edges loosely seated in the peripheral grooves, as above described, the tube with its loosely fitted fins is placed in a press having a frame adapted to hold the fins in their groove seats, each fin with its inner edges resting on the base of the groove. Pressure is then applied to the ends of the tube longitudinally thereof to thereby shorten the tube sufficiently to crush the metal in the side walls of each groove laterally into substantially 100% area contact with the fin surface thus imbedded within the peripheral wall of the tube. During this operation one end of the tube may be held stationary against a die abutment while the other end is movably compressed with all of the metal in the tube walls shifted toward the stationary end, or squeezing pressures may be simultaneously applied to both ends of the tube. Experience has shown this to be a practical and rapid method of assembling fin-tube radiators. The radiator sections are of relatively short length, and the reinforcing plates 44 and end plates 42 of Fig. 1 may serve, in conjunction with the frame of the press, to insure against any buckling of the tube.

As illustrated in Fig. 7, the above described tube crushing operation results in clamping the inner edges of the split fins into substantially integral structure with the tube walls. Each unit of surface area of the fins extending within the tube wall is gripped almost simultaneously with every other unit of imbedded fin area by the inwardly crushed side walls of the grooves, so that the operation causes no substantial distortion of the fin or shifting of metal from one imbedded portion thereof to another. The resulting joint between fin and tube is strong and has a very high heat conductivity coefficient, since the heat conductivity "neck" between fin and tube substantially corresponds in area with the imbedded surface area of the fin. The metal of the heating tube so closely adheres to the fins as to form a substantially seamless connection. Heat conduction between the fin and tube therefore takes place without interference, rapidly and uniformly in all directions. The tube may be shortened by the operation more than 10% of its original

length, and its walls are thickened somewhat, particularly in the plane of the grooves, as indicated by the internal annular ridges 48 shown in Fig. 7, as formed by crushing of metal below the base of the groove.

After the tube and fins have been assembled into an integral radiator unit by the longitudinal squeezing operation on the tube, the unit is removed from the press. Side plates 50 may then be mounted along the lateral edges of the fins but spaced therefrom to prevent scraping thereof during expansion. The end plates are attached to the side plates 42 and reinforcing plates 44 to form a protecting frame for the fins. The side plates also function to strengthen the radiator against mechanical and temperature distortion.

The heating tube with its grooves, threaded end couplings, and end plates may be die-cast as a unitary integral body. The preferred method of assembly contemplates locking the multiple sheet metal fins in the grooves of the unit by a single longitudinal squeezing operation on the tube. The assembled radiator unit has a relatively much greater metal to metal joint contact area between fin and tube than any other known heat exchange device. The type of joint between fin and tube is such that a great variety of metals can be joined, including steel and aluminum, brass and steel, and brass and aluminum.

The invention has been particularly described with relation to heat radiators employing straight tubular heating medium conduits of tear-drop cross section. It will be apparent, however, that the invention is generally applicable to heat exchange apparatus in which the flow of heat may be in either direction between the fins and heating element. Moreover the heating element need not be limited to any particular external or internal shape or section. For example, if the source of heat used is electrical current, the heating element need not be tubular providing that its length and cross section do not exceed the limits within which the walls of grooves in its periphery can be crushed to imbed fins seated therein, without undue distortion of the resulting radiator.

I claim:

1. The method of joining a radiator fin to a tubular heat exchange element which comprises, forming a groove in the wall of said element, inserting an edge of the fin therein, and crushing the walls of the groove against the embraced sides of the fin by application of a squeezing pressure to the element in a direction at substantially right angles to the groove and in amount sufficient to permanently shorten the element in the direction in which pressure is applied.

2. The method of assembling a peripherally grooved heat conductor and a sheet metal fin into an integral heat exchange body, comprising seating an edge of the fin in the groove of the conductor, and applying pressure to the conductor at right angles to the inserted fin surface of sufficient intensity to permanently shorten the conductor in the direction of pressure application and thereby crush the metal forming the walls of the groove inwardly against each unit area of imbedded fin surface.

3. The method of assembling a peripherally grooved tubular heat conductor and a plurality of sheet metal fins into an integral fin radiator which comprises, mounting said fins in spaced parallel position along the conductor, seating an edge of each fin in a groove of the conductor,

and applying pressure to the conductor at right angles to the inserted fin surface of sufficient intensity to permanently shorten the conductor in the direction of pressure application and thereby crush the metal forming the walls of the groove inwardly against each unit area of imbedded fin surface.

4. The method of assembling a peripherally grooved metal tube and a sheet metal fin into an integral heat exchange unit, comprising seating an edge of the fin in the groove of the tube, and applying a squeezing pressure to the ends of the tube to thereby permanently crush the metal forming the walls of the groove into full metal to metal contact with the imbedded surfaces of the fin.

5. A method of assembling into a fin-radiator a heating tube having spaced parallel circumferential grooves in its outer wall, and a plurality of split sheet metal fins each having an inner edge corresponding in contour and dimensions with the base of a groove, comprising mounting the fins transversely on the tube with an inner edge of each fin loosely seated in a corresponding groove, and applying a crushing pressure to the tube walls coaxially thereof, to thereby permanently shorten the tube and simultaneously cold-press the walls of all the grooves into intimate heat-conducting contact with the inserted fins.

6. The method of assembling into a radiator a heating tube having a helical groove formed in its outer peripheral wall, and a plurality of partially split sheet metal fins having inner edges corresponding in contour and dimension with the base of said groove, comprising successively threading a plurality of the fins onto the tube in transverse parallel relation along the groove, and applying a crushing pressure to the ends of the tube longitudinally thereof to thereby permanently shorten the tube and force the metal forming the walls of the groove into intimate heat-conducting contact with the imbedded portion of each fin.

7. The method of assembling a radiator including as elements a heating tube having a groove in its peripheral wall and a sheet metal fin having an inner edge conforming in contour and dimensions with the base of said groove, which comprises mounting the fin on the tube with its inner edge seated in the groove, and applying pressure to the ends of the tube to force the same toward each other and thereby form a mechanically strong and heat-conductant joint between the tube wall and the groove seated edge of the fin.

8. The method of manufacturing a fin-tube radiator which comprises, diecasting a straight metal tube section with integral peripheral grooves, loosely seating an inner edge of each of a plurality of thin metal fins in said grooves in spaced parallel relation to each other and, applying pressure to the ends of the tube of sufficient intensity to squeeze the ends toward each other and crush the side walls of the grooves into full metal to metal contact with imbedded surfaces of the fins.

9. The method of assembling a peripherally grooved tubular metal heat-conductor and a sheet metal fin into an integral heat exchange body, comprising, seating an edge of the fin in the groove of the conductor, and applying compression stress to the conductor coaxially thereof in amount sufficient to permanently shorten the same and squeeze the metal of the conductor inwardly against the imbedded fin surface.
